Charles R. Searle

UNITED STATES PATENT OFFICE.

MAURICE M. BALSAM, OF BROOKLYN, NEW YORK.

LATHE TOOL.

Application filed August 19, 1921. Serial No. 493,569.

To all whom it may concern:

Be it known that I, MAURICE M. BALSAM, a citizen of the United States, residing in the city of New York, borough of Brooklyn, in the county of Kings and State of New York, have invented a certain new and useful Improvement in Lathe Tools, of which the following is a specification.

The invention relates to tool holders adapted to be mounted on slide-rests of lathes, and the main object of the invention is to provide a removable carrier equipped with a plurality of lathe tools, adapted to be readily secured to a slide-rest in place of the usual tool-post, and arranged to permit the presentation of either of the tools to the work.

A further object is to provide means for clamping such tools securely in the carrier, and for maintaining the tools in position for effective service.

Another object is to provide an automatic stop serving as a gauge by which the presented tool will be located in proper relation to the work, and supported close to the cutting edge during the cutting operation.

A further important object is to provide means whereby the tool carrier may be easily and securely clamped to the slide-rest to present the selected tool properly, such means being additional to such automatic stop, and another object is to provide means for taking up the slack due to wear in the members of such clamping means.

The invention consists in certain novel features of construction and arrangement by which the above and other objects are attained, to be hereinafter described and claimed.

The accompanying drawings form a part of this specification and show an approved form of the invention.

Figure 1 is a face view of the carrier, equipped with several tools arranged to be presented to the work as required.

Figure 2 is a corresponding side elevation.

Figure 3 is an elevation of the rear face of the same.

Figure 4 is a section taken on the line $\alpha-\alpha$ in Figure 3.

Figure 5 is a plan view corresponding to Figure 3.

Figure 6 is an elevation showing a portion

of the side of the carrier opposite to Figure 2.

Figure 7 is an end view showing the outer face of the clamping bolt.

Figure 8 is an elevation of such bolt.

Figure 9 is an end view of the bolt, showing the inner face.

Figure 10 is an end view of one of the tool holders.

Figure 11 is a corresponding side elevation.

Similar reference numerals indicate the same parts in all the figures.

Referring to the drawings, 1 is the base of an angular bracket having a vertical portion 2 and an aperture 3 for the reception of a heavy bolt, not shown, by which the bracket may be secured to the slide-rest of a lathe, not represented but which may be of any approved type.

The bracket 2 is bored at 4 to receive the shank 5 of a clamping bolt 6 extending therethrough, and the bracket has a flange 7 located annularly to the clamping bolt, extending around the upper part of the bracket and terminating at the base 1 at each side. The inner face of the flange 7 tapers inwardly as at 8.

Held by the head 9 of the clamping bolt 6, is a vertically mounted circular disk 10 having a central opening receiving the main portion of the bolt-head 9, which is rebated annularly to receive a corresponding annular shoulder 11 on such head. The bolt is held against revolving in the bracket 2 by a screw 12 extending through the bracket from the rear with its point engaged in one of the annularly located recesses 13 bored in the inner face of the head.

On the rear face of the disk is a tapered circular boss 14 matching the flange 7 and surrounded by an annular groove 15 receiving the lip of the flange. The protruding end of the shank 5 is threaded and is received in a nut 17 bearing against the rear face of the bracket and formed on the end of a lever 18 by which the bolt may be drawn strongly rearward by throwing the lever 18 through a short arc. When the lever is thrown in the opposite direction the bolt is loosened and the disk 10 may be rotated on the bolt, and when the lever is thrown in the direction to tighten the bolt, the latter

by the engagement of its shoulder with the rebate in the disk, draws the boss 14 into strong frictional contact with the tapered flange 7 and holds the disk against rotary movement.

The disk is provided with a series of tapered sockets each adapted to receive a tool holder in which a tool is mounted and presented radially. Each tool holder comprises a conical head 19 having a screw-threaded shank 20 extending through the disk and equipped with a nut 21 by which the conical head may be drawn into its socket. A channel 22 extending diametrically across the head 19 receives the tool, and the holder is split or slotted parallel with the channel, as at 23, from the channel nearly to the end of the shank 20, so that the pressure induced by drawing the conical head 19 into the tapered socket by the action of the nut 21, contracts the channel and the tool therein is strongly gripped.

In order to hold the tool holder positively against rotation and insure the proper presentation of the tool to the work relatively to the axial line of the latter, each head 19 is provided with an arm 24, preferably integral therewith, projecting laterally therefrom on one side, and adapted to be acted upon by the inner face of the head of a screw 25 set radially in a recess 26 in the periphery of the disk and so located as to resist the tendency of the head to rotate in the disk due to the action of the tool in making its cut. The screw 25 also serves as an adjusting means for presenting the cutting edge of the tool at the desired angle to the work. The disk is shown as equipped with eight holders and carrying a cutting-off tool 27, a forming tool 28, cutters 29, 30 and 31, and a knurling tool 32. The number of holders may be varied and as the holders are interchangeable in their sockets the tools may be located as desired relatively to each other and the holders may be shaped to receive tools of any desired type.

On the rear face of the disk 10 the protruding shanks 20 of the tool holders rest successively upon a dog 33 when in position for service and are thus directly supported close to the work while making a cut. The dog 33 is pivotally mounted on the base 1 of the bracket and is held yieldingly presented in the path of the shanks 20 by a spring 34 lying beneath a handle 35 by which the dog may be retracted out of the path.

When the lever 18 is swung to free the disk 10 the latter may be rotated, clockwise in Figure 1, to present either tool to the work, the shank-ends passing idly past the dog 33 until the desired tool is presented; the shank-end of such tool is then engaged

by the dog against a reverse movement and the lever 18 swung to grip the disk to the bracket. The whole is then fed forward on the slide-rest as usual and the cut is made. A succeeding tool is then presented by similar manipulations, and if the tools are arranged on the disk in the order in which they are to be used, each will follow the other thus effecting a great saving in time and labor. The invention offers the advantages of a turret removably mounted on a slide-rest and capable of working very close to the chuck in which the piece to be treated is held in the lathe.

When through long use the clamping bolt 6 and its seats in the disk and bracket become worn to a degree requiring a longer throw of the lever 18, to the right in Figure 3, to effect the clamping than is permitted by the base 1 of the bracket, the screw 12 is withdrawn to disengage its point from its recess 13, and the clamping bolt 6 turned back to present a new recess 13 and the screw 12 again engaged. For convenience it is preferable at the completion of this clamping operation, to have the lever 18 stand approximately vertical so that it will not interfere with the action of the dog 33. The recesses 13 and screw 12 permit such adjustment.

I claim:—

1. The lathe tool described, comprising a disk rotably mounted and having a series of tapered sockets therein, a series of tool holders each mounted in one of said sockets and having a split conical head matching therein and an arm extending laterally from said head, a shank on said head extending through said disk, a nut on said shank arranged to draw said head into said socket to compress and hold a tool carried in said head, and a screw in said disk arranged to engage said arm and hold said tool holder against rotation in said disk.

2. The lathe tool described comprising a bracket adapted to be secured to the slide-rest of a lathe, a bolt mounted in said bracket and having a head, a disk rotatably mounted on said bolt and retained by said head, a nut on said bolt arranged to coact with said bracket and hold said disk frictionally against rotation, said head having recesses therein, and a screw extending through said bracket and engaged in one of said recesses to hold said bolt against rotation.

In testimony that I claim the invention above set forth I affix my signature, in presence of two witnesses.

MAURICE M. BALSAM.
